FELT ARRANGEMENT FOR HORIZONTAL
PRESS ROLL ASSEMBLIESEarl E. Berry, Beloit, Wis., assignor to Beloit Iron
Works, Beloit, Wis., a corporation of Wis-
consin

Application May 20, 1936, Serial No. 80,763

2 Claims. (CL. 92—49)

This invention relates to horizontal press roll assemblies for paper machines including felt or carrier band arrangements therefor.

More specifically this invention relates to horizontal press roll assemblies having a center roll which may or may not be heated and rolls of the plain or suction type pressed against the center roll and includes several arrangements for a looped carrier felt to direct the wet webs 10 of paper through the assemblies.

In my copending application entitled: "Horizontal press roll assembly," filed May 18, 1936, Serial No. 80,253, there is described and claimed structure for horizontal press roll sections of 16 paper machines. The structures described therein can be used in the press roll arrangements of this invention which arrangements will be herein illustrated in a diagrammatic form.

The present invention provides horizontal 20 press roll sections equipped with only a single felt for conveying a wet web of paper through the sections. Another feature of this invention includes the use of a heated roll in the assembly to reduce the viscosity of water in the paper 25 web and felt thereby making possible a freer extraction of water from the web.

It is then an object of this invention to provide a horizontal press roll assembly with a single felt for directing a web of paper through the 30 assembly.

Another object of this invention is to provide a heated press roll assembly for paper machines.

A further object of this invention is to provide 35 a press roll assembly containing three rolls in horizontal relation with the center roll adapted to be heated and at least one of the side rolls provided with a suction head.

A further object of this invention is to provide 40 a horizontal press roll assembly with various felt arrangements for handling all calipers and weights of paper.

Still another object of this invention is to extract larger amounts of water from wet soggy 45 webs than was heretofore possible without stretching or crushing the web.

Another object is to eliminate the long draw for paper webs heretofore necessary between the couch roll and press roll section of a paper 50 machine.

Another object of this invention is to reduce the viscosity of water in a wet paper web during a water extracting operation.

Other and further objects of this invention will become apparent from the following detailed

description of the annexed sheets of drawings which disclose preferred embodiments of the invention.

On the drawings:

Figure 1 is a diagrammatic side elevational view of a press roll assembly according to this invention mounted between the couch roll and drier section of a paper machine and having a suction roll adjacent the couch roll and a plain press roll adjacent the drier section. 5

Figure 2 is a diagrammatic side elevational view of another form of press roll assembly according to this invention mounted between the couch roll and drier section of a paper machine and equipped with two suction press rolls and a 15 single looped felt for directing the paper webs from the couch roll through the assembly. 10

Figure 3 is another diagrammatic side elevational view of a modified form of press roll assembly according to this invention mounted between the web forming and drier sections of a paper machine and having a heated center roll. 20

Figure 4 is a diagrammatic side elevational view of a press roll assembly according to this invention having a single looped felt disposed around the rolls of the assembly over the assembly and also having a heated drum as the center roll for the assembly. 25

Figure 5 is another diagrammatic side elevational view of a modified form of press roll assembly according to this invention mounted between the couch roll and a large drier drum of a Yankee type Fourdrinier machine with a single felt for conveying the web from the couch roll through the press roll section to the drier drum. 30 35

Figure 6 is a diagrammatic side elevational view of a modified form of press roll assembly for use in a Yankee type Fourdrinier machine as illustrated in Figure 5. 40

Figure 7 is another diagrammatic side elevational view of a press roll assembly according to this invention for use on a Yankee type Fourdrinier machine showing a modified form of felt arrangement for directing the paper web through 45 the assembly.

Figure 8 is another diagrammatic side elevational view of a press roll assembly according to this invention and having an inner felt for protecting the paper web as it passes around the 50 center roll of the assembly.

As shown on the drawings:

In Figure 1, the reference numeral 10 indicates a forming wire having a web W formed thereon. The forming wire 10 is trained around 55

a suction couch roll 11 having a suction head 11a for removing water from the web W as it passes thereover. The web W after passing over the suction head 11a of the couch roll 11 leaves the forming wire 10 and is directed under a guide roll 12 onto a carrier felt 13.

The carrier felt 13 with the web W thereon is trained over a suction roll 14 having a suction head 14a mounted in advance of the roll 14 and a center roll 15. As the web and felt pass over the suction head 14a of the suction roll 14 water is removed therefrom by suction. As the web and felt then advance through the nip of the rolls 14 and 15 additional water is removed from the web by pressure. This water is simultaneously removed from the nip into the suction head.

The web W and felt 13 pass around the bottom portion of the center roll 15 with the web contacting the periphery of the center roll. The web and felt then pass up through the nip of the center roll 15 and a plain press roll 16 in peripheral pressure relation with the center roll 15. The felt 13 is then separated from the web and passes around the plain press roll 16. The web alone then passes through the nip of the center roll 15 and a smoothing roll 17 mounted above the center roll where the web is ironed out and felt marks removed from the surface thereof. The web follows around the smoothing roll 17 into the drier drum section 18 of the machine.

Wiping devices 15a and 17a respectively contact the peripheries of the center roll 15 and the smoothing roll 17 to remove water and foreign material therefrom.

The center roll 15 is stationarily but rotatably mounted on a base 19 which base 19 pivotally carries standards 20 and 21 for pivotally supporting the suction roll 14 and the plain press roll 16 respectively. It is thus obvious that the suction roll and the plain press roll can be swung about their pivot points in and out of pressure relation with the center roll 15.

Feet 20a and 21a are provided on the standards 20 and 21 to limit the backward movement of the suction roll 14 and press roll 16 away from the center roll 15.

The single carrier felt 13, which is trained over the suction roll 14, under the center roll 15 and over the plain press roll 16 is also trained around a tensioning roll 22 for maintaining the felt in a proper taut condition, and over guide rolls 23 and 24 located adjacent to the couch roll 11 for directing the felt into close relationship with the couch roll so that the web W will not have a long draw between the couch roll and the press roll assembly.

One of the standards 20 for the suction roll 14 has a manifold suction head communicating with a vacuum pump for evacuating the suction head 14a in the roll.

In Figure 2 parts identical with those described in Figure 1 have been marked with the same reference numerals and need not be further described.

However, in Figure 2 a second suction press roll 25 having a suction head 25a is used in place of the plain press roll 16 described in Figure 1. Furthermore, the felt 13 after passing under the center roll 15 is directed away from the web

W around a guide roll 26 which directs the felt alone over the suction head 25a of the suction roll 25 where water is removed from the felt before it re-contacts the web W as the web and felt pass through the nip of the rolls 15 and 25.

In this manner the suction head 25a serves to

dry the felt so that it can readily absorb water from the web as the water is squeezed out of the web by its passage through the nip of the rolls 15 and 25.

The suction roll 25 is supported on standards 5 such as 27 one of which has a manifold chamber therein in communication with a vacuum pump (not shown) for evacuating the suction head 25a of the roll.

After passing through the nip of the rolls 15 10 and 25 the web W is directed over a guide roll 28 and then through a pair of wringer or smoothing rolls 29 into the drier section 18.

The second suction press of the assembly shown in Figure 2 acts as a felt conditioner, opening up 15 the pores of the felt and making it readily receptive for the absorption of water squeezed from the web. If desired, a smoothing roll can be mounted either against the top of the center roll 15, or against the bottom of the center roll, 20 or against both the top and bottom of the center roll.

In Figure 3 the reference numeral 30 indicates a Fourdrinier forming wire having a web W formed thereon. The wire 30 is trained around 25 a suction couch roll 31 over a suction head 31a therein. A top carrier felt 32 is disposed over the forming wire 30 and directed under a top couch roll 33 cooperating with the couch roll 31 to transfer the web W from the wire 30 to the 30 felt 32.

If the web W is a light-weight paper such as a tissue, the felt 32 conveys the web as shown in solid lines over a suction roll 34 of the press section having two suction heads 35 and 36. The web under the felt 32 contacts a second felt 37 trained around the suction roll 34 before the same reaches the suction area defined by the suction head 35 of the roll. The web then passes between the felts 32 and 37 over the suction 40 head 35 where water is removed by the combined action of suction and squeezing provided by a top roll 38 acting against the suction roll 34. The felt 32 is then removed from the web W around the roll 38.

The web W is then carried by the felt 37 over the suction area defined by the suction head 36 of the suction roll 34 and through the nip of the suction roll 34 and a heated center roll 39 where additional water is removed by combined action 50 of pressure and suction.

The web and felt 37 then travel around the roll 39 where the same are heated by the roll to reduce the viscosity of water entrained therein. The felt 37 is then separated from the web 55 W and passes around a guide roll 40 and upward therefrom into contact with a second suction roll 41 having a suction head 41a for sucking water from the heated felt. The felt then re-contacts the web W on the center roll 39 as the web and 60 felt pass through the nip of the roll 39 and the suction roll 41 where water is readily squeezed from the web since its viscosity is reduced by heating and the thus extracted water immediately absorbed by the dried felt.

The felt 37 travels around the suction roll 41 and the web W follows the center roll where it is removed therefrom by a scraper 42 to crepe the web.

The contacting of the web W with the heated 70 periphery of the center roll 39 after the web is separated from the felt 37 further dries the web. The creped web is directed around a guide roll 43 and into the drier drum section 44.

The heated center roll 39 is rotatably mounted 75

on a support 45 to which are pivoted standards such as 46 and 47 for the suction rolls 34 and 41 respectively. The standards 46 and 47 have suction manifolds therein for connecting the suction head to the rolls with a vacuum pump (not shown).

In the manufacture of heavier papers the top felt 32 may be dispensed with and the heavier web W directed under a guide roll shown in dotted lines at 48. The suction head 35 of the suction roll 34 can be shut off and the heavier web directed onto the carrier felt 37 without the aid of the top felt 32. The heavier web passes through the press roll assembly in the identical manner described above in connection with the lighter tissue web until the same has passed through the nip of the rolls 39 and 41. The heavier web, instead of following the center roll 39 to the creping scraper 42, is pulled from the center roll 39 and directed over a guide roll 49 for direct passage into the drier drum section 44.

The felt 37, after passing around the suction roll 41, is directed downward around a tensioning roll 50 which maintains the felt in a desired taut condition. After passing around the tensioning roll 50 the felt travels upward over an automatic guide roll 51 which properly centers the felt on another guide roller 52 for guiding the felt into the press roll assembly.

From the above description of Figure 3 it should be understood that the modifications of operation for the structure therein provides a very flexible apparatus which can be used on light or heavy paper webs by merely throwing a top felt in and out of operation.

In the modification illustrated in Figure 4, parts identical with those described in Figure 3 have been marked with the same reference numerals. In Figure 4, the heated center drum 39 of the press roll assembly has suction press rolls 34 and 41 pivotally mounted on each side thereof and provided with suction heads 34a and 41a respectively mounted in different positions than shown in Figure 3 for the accommodation of a different felt arrangement. The modification shown in Figure 4 is intended for treating light-weight papers only such as tissue paper.

As shown in Figure 4, the light-weight web W 50 on the Fourdrinier forming wire 30 passes over the suction area defined by the suction head 31a of the suction couch roll 31 and is transferred onto an absorbent carrier felt 55 by means of a transfer roll 33.

The web W then travels with the felt 55 under a guide roll 56, over the suction area provided by the suction head 34a of the suction press roll 34 where water is removed from the web through the felt by suction. The web and felt then pass through the nip of the rolls 34 and 39 where additional water is extracted therefrom by pressure.

The web and felt then travel with the heated center roll 39 around the top thereof where the same are heated by contact therewith to reduce the viscosity of the water therein. The felt 55 is separated from the web W and passes over a guide roll 57 while the web follows the heated drum. The felt is then directed over the suction area provided by the suction head 41a of the suction press roll 41 where water is removed therefrom by suction and the felt is opened up and conditioned for absorbing water from the web as it recontacts the web in the nip of the rolls 39 and 41. The felt and web pass through the

nip of these rolls together where water squeezed from the web is readily absorbed into the felt and the felt is then immediately again separated from the web and passes around the suction roll 41 up over guide rolls such as 58 back to the couch roll of the web forming section. The web is scraped from the drier roll 39 by means of a scraper 59 which may also crepe the web. The creped web then passes into the drier drum section 44.

The modification shown in Figure 4 therefore provides for the use of a single felt to carry light-weight paper through the press roll assembly.

In Figure 5 another modification of the invention is illustrated in which a single looped carrier felt conveys the paper web through the press roll section and deposits the same to the top side of a large diameter Yankee drier.

As shown in Figure 5 the Fourdrinier forming wire 60 having the web W formed thereon passes around the suction couch roll 61 over the suction head 61a thereof. A top couch roll 62 cooperates with the suction head 61a of the couch roll 61 to transfer light-weight webs directly onto a top carrier felt 63. The felt 63 picks up the light-weight web W and conveys the same onto a carrier felt 64 trained around the suction press roll 65 having a suction head 65a therein.

When a heavier web W is formed on the wire 60 the top couch roll 62 can be raised to the position shown in dotted lines so that the felt 63 will not contact the web until the same is already deposited on the carrier felt 64. In this arrangement for heavier webs the heavier web W' is removed from the couch roll 61 and under a small guide roll 66 and deposited directly onto the carrier felt 64 without the aid of the top felt 63.

The web W or W' then passes while covered with the felts 63 and 64 through the nip of the suction press roll 65 and a center heated roll 67 where water is removed from the web by suction and pressure. The web and felts then hug the under part of the heated roll 67 to the bottom thereof where the outside felt 64 is removed from the web and directed around a guide roll 68 while the inside felt 63 continues to hug the heated roll 67 and carries the web thereon.

The felt 64 is directed against a second suction press roll 69 and over the suction area defined by the suction head 69a thereof where water is removed therefrom by suction. The felt 64 then re-contacts the web as the same passes through the nip of the rolls 67 and 69 where it rapidly absorbs water from the web.

The felt 63 follows around the upper portion of the heated roll 67 back over the Fourdrinier wire while the web is transferred onto the felt 64 and follows the felt around a roll 70 which deposits the web onto the large Yankee drier 71.

The web 64 then returns to the suction press roll 65 over a guide roll 72, under a tensioning roll 73 and over an automatic guide roll 74.

The web W travels around the drier drum 71 where it is heated and dried by contact therewith and is then either pulled off of the drier or a guide roll 75 or is scraped off of the drum by a creping doctor 76. A second doctor or wiper 77 is also provided on top of the drum 71 to clean the same.

The modification shown in Figure 5 is therefore adapted by simple adjustments to treat all weights of paper. This modification can be further revised to use a plain press roll in place of the second suction press 69. When a plain press

roll is used, the guide roll 68 can be dispensed with thereby allowing the felt 64 to hug the center roll 67 until it passes through the nip of the center roll 67 and the plain press roll.

5 The side rolls 65 and 69 are pivotally mounted and adapted to be swung into any desired pressure relation with the center roll 67 as described in Figures 3 and 4.

10 In the modification shown in Figure 5 the top felt 63 follows entirely around the periphery of the center roll 67. The web is therefore protected between two felts when it passes through the nip of the press rolls in the assembly.

15 In the modification shown in Figure 6 parts identical with the elements described in Figure 5 have been marked with the same reference numeral.

20 In the structure shown in Figure 6, however, the top felt 63a does not pass around the center roll 67 but instead merely picks up light-weight webs W from the forming wire 60 and conveys the same onto the carrier felt 64.

25 The first suction press 65 is provided with two suction heads 65a and 65b for defining separate suction areas. The top felt 63a and the carrier felt 64 direct the web over the suction area defined by the suction head 65b where water is removed from the felts and web by suction. A top press roll 78 cooperates with the suction area defined by the suction head 65b of the roll 65 to squeeze additional amounts of water from the felts and web. The top pick-up felt 63a follows around this roll 78 back over the forming wire 60 while the web travels with the felt 64 through 30 the press roll assembly and is deposited onto the drier drum 71 identically in the manner described in connection with Figure 5.

35 If heavier webs W' are formed on the wire 60 the upper couch roll 62 is raised as shown in Figure 40 dotted lines so that the pick up felt 63a will not contact the heavy web until the same is deposited on the carrier felt 64. The pick-up felt 63a then merely serves to protect the heavy web as it passes through the nip of the rolls 65 and 78.

45 In the modification illustrated in Figure 7 a single felt is used and transfers the web from the forming wire to the bottom side of a large Yankee drier as well as directs the web through the press roll section.

50 In Figure 7 the reference numeral 80 indicates a forming wire having a web W formed thereon. The wire 80 is trained around a suction couch roll 81 having a suction head 81a therein and a top roll 82 cooperating therewith for transferring the web W from the wire 80 to a carrier felt 83.

55 The web W and felt 83 are then passed under a guide roll 84 and up over a suction roll 85 having a suction head 85a therein for removing water from the web through the felt 83. The web and felt then pass through the nip of the suction press roll 85 and a heated center roll 86 where additional water is removed therefrom by pressure. The web and felt then follow around the periphery of the heated roll 86 with the web in contact with the periphery of the roll. The web and felt are thus heated to reduce the viscosity of the water entrained therein and make possible a freer extraction of the water therefrom. The felt 83 is momentarily removed from the web W and passes over a guide roll 87 while the web hugs the heated roll 86.

70 The felt 83 is directed by the roll 87 against a second suction press roll 88 and over the suction head 88a therein where water is sucked from the felt to dry the same and to open up

the pores thereof. The felt then recontacts the web as the same passes through the nip of the rolls 86 and 88 and readily absorbs water squeezed from the web. The water absorbed into the felt is removed by suction through the suction head 88a.

75 The web and felt then pass under a guide roll 89 and travel toward a large Yankee drier 90. A transfer roll 91 is provided for receiving the web and felt to transfer the web from the felt 10 onto the periphery of the drier 90. The felt then travels back to the forming wire and the web travels around the drier drum 90 where it is dried by contact with the heated drum. The web is pulled from the periphery of the drum 15 around a roll 92 or can be scraped from the drum by a creping doctor 93. A second doctor 94 is provided for wiping the periphery of the drum clean.

20 If desired a wiper 95 can be urged against the periphery of the heated roll 86 to clean the same.

25 In the modification illustrated in Figure 8 the arrangement is substantially identical with that described in Figure 7 and identical parts have been marked with the same reference numeral.

30 However in Figure 8 the heated drum 86 is provided with a bottom felt 96 which is trained around the periphery thereof so that the web will be carried between two felts as it passes around the heated roll between the suction presses.

35 The felt 96 is directed into contact with the web W on the felt 83 by a guide roll 97 mounted under the suction press 85. The felt 96 thereupon covers the web W on the felt 83 as the same passes through the nip of the rolls 85 and 86 35 and acts as the bottom felt for the entire travel of the web around the periphery of the center roll 86. The felt 96 is removed from the center roll 86 over a guide roll 98 and under a tensioning roll 99. If desired a wiper or scraper 100 40 can act against the periphery of the center roll 86 after the felt 96 has been removed therefrom over the roll 98. The scraper or wiper will serve to clean the periphery of the roll 86.

45 The use of the felt 96 serves as an added protection for the web in its passage through the nips of the press rolls and around the periphery of the center roll.

50 From the above description it should be understood that this invention provides practical felt arrangements for horizontal press roll assemblies and also provides for the use of a heated drum in the assembly to lower the viscosity of water entrained in the web and carrier felts therefor.

55 I am aware that many changes may be made and numerous details of construction may be varied through a wide range without departing from the principles of this invention, and I, therefore, do not purpose limiting the patent granted 60 hereon otherwise than necessitated by the prior art.

65 I claim as my invention:

1. In a web dewatering press roll assembly having a free-draining nip allowing gravity drainage of water therefrom and not requiring crowning of the rolls to offset against vertical deflection thereof for maintaining uniform nip pressures throughout the lengths of the nips therebetween including a center roll and rolls on 70 each side of said center roll in horizontal alignment therewith to define a pair of substantially vertical pressure nips, at least one of said rolls being a suction roll having a suction area at the nip partially defined thereby, and at least one 75

guide roller spaced from the assembly, the improvements which comprise an endless looped felt trained around the guide roller and around said rolls to lap portions of the peripheries of each of said rolls for conveying a wet web of paper through the entire assembly and between the nips thereof in opposite substantially vertical directions while covering the web as it passes around the center roll, and a directing roll outside of the loop of said felt adjacent said suction roll for receiving the felt from the center roll to direct the felt alone over said suction area before recontacting the web whereby the felt will be dewatered.

2. In a web dewatering press roll assembly having a free-draining nip allowing gravity drainage of water therefrom and not requiring crowning of the rolls to offset against vertical deflection thereof for maintaining uniform nip pressures throughout the lengths of the nips

therebetween including three rolls in horizontal alignment providing a substantially vertical upward passage nip and a substantially vertical downward passage nip, the improvements which comprise a single guide and tensioning roller spaced beneath the assembly, and a looped felt trained around said guide and tensioning roller and around said rolls to lap portions of the peripheries of each of said rolls, said guide roller and the end rolls of said three-roll press assembly being within the loop of said felt and the center roll of said assembly being outside the loop of the felt to effect only a single reverse bend in the loop for conveying a wet web of paper through the entire assembly and through the nips in substantially vertical directions while covering the web as it passes between the nips to cause the same to hug the center roll without undue flexing of the felt.

EARL E. BERRY. 20

CERTIFICATE OF CORRECTION.

Patent No. 2,209,757.

July 30, 1940.

EARL E. BERRY.

It is hereby certified that error appears in the printed specification of the above numbered patent requiring correction as follows: Page 2, first column, line 9, before "roll" insert --nip of the--; and that the said Letters Patent should be read with this correction therein that the same may conform to the record of the case in the Patent Office.

Signed and sealed this 10th day of September, A. D. 1940.
